UNITED STATES PATENT OFFICE.

JOHN D. CURTIS, OF WORCESTER, MASSACHUSETTS.

ELECTRIC WELDER FOR WIRE-FENCE MACHINES.

SPECIFICATION forming part of Letters Patent No. 495,626, dated April 18, 1893.

Application filed November 2, 1892. Serial No. 450,797. (No model.)

To all whom it may concern:

Be it known that I, JOHN D. CURTIS, a citizen of the United States, residing at Worcester, in the county of Worcester and Commonwealth of Massachusetts, have invented a certain new and useful Improvement in Barbed-Wire Machinery, which improvement is fully set forth in the following specification.

10 The object of my invention is to manufacture barbed wire without splices, thus avoiding the frequent stoppage of the machines, necessary when splices are made. This I accomplish by welding, electrically, 15 the pieces of wire forming the continuous strand of the fencing.

In the drawings, Figures 1, 2 and 3 represent in plan barbed wire machines of ordinary construction such as are very commonly 20 used.

The two wires which form the twisted cable fencing are taken from the reels at the rear of the barbing machines, indicated in plan at 4, 5 and 6, Fig 2. Barbing machines 1 and 25 3, are also provided with reels in the same way, although they are not shown in the drawings.

The two wires 7 and 8 are fed into the barbing machine through the feed-roll 9 at the 30 rear of the machine, and in the direction of the arrow, the wire 8 passing through the winding spindle 10, where the barb is wrapped around it, the wire forming the barb being fed into the machine in the usual manner, 35 substantially at right angles to the main wire through the feed-rolls 11. The naked wire 7 and the wire 8, with the barbs attached to it, are then twisted together in the usual manner by a twister of the ordinary form, which 40 is not shown in the drawings, placed at a suitable distance in front of the barbing machine.

It is obvious that when the wire on the reels at the rear of the machine is used up, new coils must be supplied and spliced to the wire 45 which has passed through the machine and which is partially wound upon the spool in the twister. It is evident that this splice cannot be made behind the machine, because if it were, the wires could not pass through the 50 feed rolls 9, nor could the wire to be barbed pass through the winding spindle 10; consequently, the necessary practice is to make the

splice between the barbing machine and the twister. In practice, when a wire runs out, the twister is stopped, a new wire is introduced into the machine, the loose end of the wire already partially wound upon the spool in the twister and the new wire coming from the machine are then spliced by a hand tool and the twister and machine are then started 60 and continue in operation until it is necessary to make another splice. These splices are so objectionable that only wire of long lengths can be profitably used in the manufacture of barbed wire; but even in using 65 the longest lengths practicable, one or more splices occur in every spool.

Not only are splices objectionable because of the delay occasioned in making them, thus decreasing the product of the machines, but 70 they weaken the fence at the points where they are made, increase the weight of the fence, and consequently diminish the number of feet in a given number of pounds bought by the consumer. Furthermore, the splices detract from the good appearance of the fencing when it is used. A great objection to the present method of splicing, to the manufacturer, is that the delay thus occasioned, greatly increases the cost of manufacturing the fencing, and consequently makes it unprofitable to use short lengths of wire. Moreover, 75 there is always more or less waste in splicing, in cutting the ends of the wire to the same length, after the splice is made. All 80 these serious objections to the present method of manufacture are obviated by my improved mechanism, in which I use a dynamo of suitable power, shown in plan at 12, in the drawings, from which the necessary connections 85 are made in any convenient manner with welding machines, 13, 14 and 15, each attached to one of the barbing machines.

In the drawings I show three barbing machines, which may be run by one attendant. 95 When a coil of wire is nearly run out, it is only necessary for the attendant to place the ends of the old and new coils in the welding apparatus, as indicated at 16, Fig. 2, and after welding them in the usual manner he allows 100 the wire to pass through the machine, which may be kept running during the operation.

As no more than one machine is likely to need attention at a time, it is apparent that

three machines, or as many as may be in the charge of one attendant will run continuously till the spools in the twisters are of the desired weight, when they are removed, and 5 others put in their place and the operation continued.

By my improved mechanism barbed wire may be produced of any length without 10 splices, and of uniform strength, and, if desired, from short lengths of wire, at much smaller cost both to the manufacturer and consumer, than by the present method.

I do not restrict myself to any particular 15 form of barbing machines or to twister, nor 20 to any particular arrangement of the two, nor to the particular arrangement of the reels holding the smooth wire which is fed into the barbing machines, my arrangement of mechanism being applicable to all styles 25 of barbing machines and to any number.

While my improvement is more particularly designed for use in connection with a 25 barbed wire machine, it may be used with equal efficiency in connection with machinery designed to produce barbless fencing.

In practice I prefer to use three reels at the rear of each machine so that the attendant may more conveniently make his welds without stopping the machine or snarling his wire.

What I claim as new, and desire to secure 30 by Letters Patent, is—

1. In a barbed wire machine, the combination with the barbing mechanism, of an electric welder intermediate of the barbing mechanism and the wire supply mechanism, whereby unbroken lengths of wire may be fed to 35 the barbing mechanism, substantially as described.

2. In a machine for making wire fencing, the combination with the wire feeding mechanism, of an electric welder intermediate of the wire feeding mechanism and the wire supply mechanism, whereby unbroken lengths of wire may be supplied to the wire feeding mechanism, substantially as described. 40

JOHN D. CURTIS.
